REINFORCED WIRE-CONTACTING
INSULATOR ASSEMBLY

Rogers Case, Orange, N. J.

Application November 24, 1945, Serial No. 630,588

2 Claims. (Cl. 174—209)

1

This invention relates to a wire-contacting insulator assembly reinforced by additional protection against short-circuiting if the main electrically insulating body of the assembly should be broken.

Tensioning and transposition brackets for communication lines are made to be mounted in the lines between poles in suspended relation with the wires. When brackets of that sort are organized to include insulators of general spool form, those insulators are made of some highly frangible material, such as glass or porcelain, and are mounted on a metal base by means of metal insulator pins. Breakage of such insulators is relatively frequent and may be caused by accident, mischief, or malice; and when an insulator which is incorporated as an element in a metal tensioning or transposition bracket of the indicated sort is broken, such breakage is almost sure to result in a short-circuit. This is because relative movement between the line wire and the base of the bracket when the insulator is broken and the relief of the tension under which the wire is held brings it into contact with the metal pin on which the insulator is mounted, or into contact with some other metal part of the bracket.

The primary object of my invention is to provide in line-tensioning and transposing bracket assemblies and other mounted wire-contacting insulator assemblies, insulator structures comprising what may be considered as insulation reinforcement, or emergency insulation, to prevent short-circuiting when the frangible body of an insulator is broken, and to keep the line in service until the broken insulator is replaced.

A corollary object of the invention is to provide such insulation reinforcement, or emergency insulation, by means of a simple and inexpensive addition to the insulator structure.

In the accompanying drawings illustrative of a physical embodiment of my invention:

Fig. I is a plan view of a tensioning and transposition bracket constructed to be mounted in communication lines, and showing the improved insulator structure of my invention incorporated as an element thereof.

Fig. II is an end elevation of the transposition bracket shown in Fig. I, looking upwardly of the sheet.

Fig. III is an enlarged cross-sectional view through the structure at one side of the bracket, taken in the plane of the section line III—III of Fig. I, and showing the body of one insulator removed as by breakage, to illustrate the man-

2

ner in which a short-circuit is prevented under that condition.

The transposition bracket shown in the drawings is, save for the improvement of my present invention, made in accordance with my prior Patent No. 2,356,750. Thus it comprises a metal frame, or base, 1 on which a plurality of spool-form insulators 2, 3, 4 and 5 are mounted in approximately rectangular arrangement in their position relatively to each other. The insulators 2 and 3 form one diagonally arranged pair extended upwardly from the base 1, and insulators 4 and 5 form a second diagonal pair extended downwardly from the base 1. Each of the insulators is carried by a bolt, or pin, 6 which as shown comprises a head 7, and is secured in position by a cotter pin 8.

In service position of the transposition bracket it is suspended on the line wires A and B of a communication line, with the line wires A and B transposed in their relative position in the line by being trained respectively around the two diagonal pairs of insulators 2—3 and 4—5. Thus the line wire A is trained over insulator 2 and diagonally across the line spaced by the bracket to and against insulator 3. Both of these insulators 2 and 3 extend upwardly from the base 1 of the bracket. Similarly the line wire B is trained over insulator 4 and brought diagonally across the bracket and across line wire A to insulator 5 around which it passes. It readily will be understood that the line wires trained over the insulators are placed under tension and exert a bending force on the pin 6 of each insulator. To oppose this destructive pull of the line wires, and to prevent bending of the insulator pins, each of the pins is braced in opposition to the forces exerted by the wire which is trained against it by a metal brace 9 riveted to the base 1 and engaging the pin 6 of the insulator.

In service the transposition bracket thus is suspended on the line wires with one wire, such as the wire A, overlying the metal base of the bracket, and the other wire, such as the line wire B, underlying the base of the bracket. The width of the bracket and the spacing of the line wires normally is such that both wires are placed under tension. On breakage of either of the insulators 4 and 5 a short-circuit is formed by direct contact between the wire B and a metal part of the bracket. This is because the tension under which the wire is placed brings it inwardly into contact with the pin 6 of the broken insulator. Also relative movement between the wire and the bracket causes the wire to move

along the insulator pin 6 into contact with the metal base 1, so that even if the insulator pin should be insulated from the base, or the wire should escape direct contact with the pin, a short-circuit is made. In the case of the line wire A which overlies base 1 of the bracket, the formation of a short-circuit when one of the insulators 2 or 3 is broken also is almost certain. This is because the tension of the wire and tilting of the bracket when the insulator is broken brings that wire into contact with the metal pin 6 of the broken insulator, and finally into contact with one of the metal braces 9 which support the insulator pins against the bending forces exerted on them by the wire.

The problem arising from the danger of short-circuiting by breakage of an insulator being serious, various expedients have suggested themselves for preventing short-circuiting when an insulator is broken. One such expedient is to insulate the base of the bracket and the insulator pins by applying to them a coating of vitreous enamel. Such expedient is relatively expensive and is ineffective, because a vitreous coating on the base and insulator pins of the bracket is itself susceptible to breakage, chipping and spalling. I have discovered, however, that in a wire-tensioning and transposition bracket the danger of short-circuiting upon breakage of an insulator can in practical effect be eliminated by very simple and inexpensive means. Such means consists of a liner sleeve, such as the liner sleeve designated by reference numeral 10 in the accompanying drawings, which is composed of tough electrical insulating material, and which surrounds the mounting pin of each insulator to lie between the pin and the insulator body.

Referring to the drawings, it will be seen that the tubular portion of liner 10 is provided at one end with a laterally extended flange, or skirt, 11 which lies against the upper end of the insulator body to surround the pin-receiving bore 12 therethrough. As shown particularly in Fig. III of the drawings, laterally extended flange, or skirt, 11 of the liner sleeve lies in a countersunk seat, or outwardly open recess, 13 formed in the structure of the insulator body around the bore therethrough. In the bracket assembly shown, the liners 10 are so arranged in the bodies of the insulators that their extended skirts 11 are at the upper ends of the insulator bodies. That is, in the case of the insulators 2 and 3, flanges 11 of the liners forming part of those insulators are between the upper end of the insulator and the braces 9 which engage the insulator pin of each. In the case of insulators 4 and 5 which extend downwardly from the base 1 of the bracket, the flanges 11 of the liners 10 forming part of those insulators lie against the end of the insulator body which is adjacent the under surface of the base.

Assuming that the body of one of the insulators 2 or 3 which extend upwardly from base 1, or of the insulators 4 or 5 which extend downwardly from base 1, be broken, the wire trained around the broken insulator tends, as previously described, to move both upwardly and inwardly with respect to the base of the insulator. Also the base of the insulator tends to tilt as the balancing effect of the symmetrical grouping of the insulators with respect to the line wires is lost. If the insulator be merely cracked, or there be a gap in it, there may be no substantial relative movement between the base of the bracket and the wire, and in such case the tubu-

lar portion of liner sleeve 10 of the broken insulator prevents short-circuiting between the wire and the insulator pin, because of its embracing relationship with the pin. If, however, there be movement of the sort described, which usually will occur if the broken insulator body be entirely detached from its pin, the wire moves inwardly until it rests against the tubular portion of the liner, and in its upward movement reaches and comes to rest at the junction between the tubular portion of the liner and the flange, or skirt, which projects laterally from it. This prevents short-circuiting contact between the wire and the base, or a brace of the bracket structure, as well as short-circuiting contact with the insulator pin.

The organization of the liner sleeve to include a lateral flange, as well as a tubular pin-embracing portion, is of particular importance when the insulator assembly forms an element of a tensioning and transposition bracket made in accordance with my prior Patent No. 2,356,750, as shown in the drawings. This is because breakage of the frangible body of one of the insulators makes a short-circuit almost inevitable in the absence of means effective to prevent short-circuiting. It is, however, highly desirable in insuring against short-circuiting in any tensioning or transposition bracket which in its mounted position is supported by the line wires inasmuch as it positions the wire with respect to the metal structure of the bracket so that a short-circuit will not be made between a line wire and a metal part of the bracket by relative movement between the bracket and the wire, if the frangible body of an insulator be broken.

Specifically considered, the material of which the liner is composed is not critical. Qualitatively the composition of the liner is of importance, because it is necessary that the liner should possess the property of electrical insulation coupled with substantial toughness, inasmuch as its function is to prevent short-circuiting when the frangible body of the insulator is broken. A number of suitable materials are at hand and in common use in the electrical arts. A material I have found ideal for the composition of the liner is the hard red vulcanized fiber which is used in bushings, washers, grommets, and the like, in electrical equipment. Other suitable tough materials having the property of electrical insulation, such as molding materials composed of plastics and asbestos fiber and the like compressed and strong materials possessing good electrical insulating properties, may be used. These properties are possessed by the hard vulcanized fiber referred to above, by "Micarta" and by other plastic compositions well known in the electrical art.

I do not advance the use of such materials to be new in electrical assemblies, their existence and previous use in such general associations being above expressly acknowledged. Primarily my invention resides in the discovery that in a metal tensioning or transposition bracket for electrical line wires, a tough electrically non-conductive insulator liner as above disclosed will, upon breakage of the frangible insulator body with which it is associated, effectively prevent short-circuiting; and that it will do so in spite of a tendency for the wire to move into direct contact with the metal structure of the bracket when the insulator is broken.

It is to be understood that by the term "spool-form," as used herein to describe the bodies of

the insulators, I do not mean to define any specific shape of insulator, but intend the term to define any of the well known insulators which are circular in horizontal section, and which are provided exteriorly with at least one wire-receiving groove, and which have an interior bore for mounting an insulator body on a pin. Many specific insulator structures commonly in use are comprised within the term "spool-form" as used herein.

I claim as my invention:

1. A wire-contacting insulator assembly consisting essentially of a metallic insulator-mounting pin, a frangible spool-form insulator body having a circumferential conductor receiving groove and a pin-receiving bore extended therethrough mounted on and surrounding said insulator-mounting pin, and a tough electrically insulating liner sleeve arranged to contact and detain a wire trained on the insulator when the said frangible insulator body is broken comprising a tubular pin-embracing portion surrounding the insulator-mounting pin within the bore of the insulator body and a wire-detaining skirt extended laterally outward from the said tubular portion at one end of the bore through the said insulator body.

2. A wire-contacting insulator assembly consisting essentially of a metallic insulator-mounting pin, a frangible spool-form insulator body 30

having a pin-receiving bore extended therethrough mounted on and surrounding said insulator-mounting pin, said bore being laterally extended at one end thereof to provide an outwardly open countersunk seat in the said frangible insulator body, and a tough electrically insulating liner sleeve arranged to contact and detain a wire trained on the insulator when the said frangible insulator body is broken comprising a tubular pin-embracing portion surrounding the insulator-mounting pin within the bore of the insulator body and a wire-detaining skirt extended laterally outward from the said tubular portion at one end of the bore through the insulator body and lying in the said countersunk seat in said body.
